TOASTER

Ivar Jepson, Oak Park, and Robert Davol Budlong, Skokie, Ill., assignors to Sunbeam Corporation, Chicago, Ill., a corporation of Illinois

Application March 24, 1950, Serial No. 8,734

Term of patent 14 years

(Cl. D81—10)

To all whom it may concern:

Be it known that we, Ivar Jepson and Robert Davol Budlong, both citizens of the United States, said Ivar Jepson being a resident of Oak Park, county of Cook, and State of Illinois, and said Robert Davol Budlong being a resident of Skokie, county of Cook, and State of Illinois, have invented a new, original, and ornamental Design for a Toaster, of which the following is a specification, reference being had to the accompanying drawings, forming part thereof.

In the drawings:

We claim:

The ornamental design for a toaster, substantially as shown.

IVAR JEPSON.

ROBERT DAVOL BUDLONG.
